INVENTOR -

Vital Gelineau,
By Albert M. Moore,
His Attorney.

UNITED STATES PATENT OFFICE.

VITAL GÉLINEAU, OF LOWELL, MASSACHUSETTS.

ELEVATOR.

SPECIFICATION forming part of Letters Patent No. 373,285, dated November 15, 1887.

Application filed April 28, 1887. Serial No. 236,403. (No model.)

To all whom it may concern:

Be it known that I, VITAL GÉLINEAU, a citizen of the United States, residing at Lowell, in the county of Middlesex and Commonwealth 55 of Massachusetts, have invented a certain new and useful Improvement in Elevators, of which the following is a specification.

My invention relates to elevators; and it consists in the means hereinafter described of preventing the elevator-car from falling when the lifting-rope is broken.

In the accompanying drawings, Figure 1 is an isometric view of an elevator-car provided with my improvement, showing one of the 15 guide-standards, a part of two of the rack-standards, and two of the dogs; Fig. 2, a vertical central section of the floor and floor-framing of the car, of the upright at the left, and of parts of the guide-standards and of 20 parts of the rack-standards at the farther side of the car, the cross-bar and one of the uprights being in elevation, and the dogs being represented as in engagement with the racks of the rack-standards; Fig. 3, a side elevation 25 of the car and vertical central sections of the guide-standards and of two of the rack-standards, the dogs being held out of engagement with the racks; Fig. 4, a side elevation of one of the tubes which contain the dogs and springs 30 and a vertical section of the bars which connect the dogs in pairs; Fig. 5, a plan of the dogs, the bars which connect them, the springs which operate them, and a horizontal central section of the tubes which contain the dogs 35 and springs, and a plan of the lower part of the double bell-crank lever and the connecting-rods which connect the lower arms of said lever to the connecting-bars of the dogs.

The car A, having the rectangular platform 40 a, uprights a', and cross-bar a'', connecting the upper ends of said uprights, is of any ordinary construction, the car being guided by vertical guide-standards B, arranged one at each side of the car, said guide-standards being provided with vertical grooves b, into which enter guide-rolls a'', journaled at the top of the uprights a' in the usual manner. In addition to the guide-standards B there are 45 four rack-standards, C, placed at the sides of the car vertically, each of the standards C being provided on its inner face with a vertical groove, c, into which grooves project dogs

D D', carried in the platform of the car, the rack-standards serving, with the dogs, to guide the lower part of the car and to confine the car 55 to a vertical path.

The dogs D D' are connected in pairs by bars d d', as shown in Fig. 5, the dogs sliding in tubes secured in the platform a of the car below the floor of the same, the tubes being slotted at e e' 60 to allow of the movement of the bars d d'. Between each dog and a dog of the other pair is arranged a spiral spring, F, within one of the tubes E, these springs normally throwing the dogs outward and into engagement with vertical racks c', said racks being arranged one in each groove c. The teeth of the racks c' are slightly hooking upward, as shown, and the outer ends of the dogs D D' are bent outward and downward and outwardly beveled 65 upward, as shown at d' d'' in Fig. 4, so that when the outer ends or points of the dogs are partially engaged with the racks c' the weight of the car and the shape of the rack-teeth and dogs would draw the dogs still farther outward and prevent the descent of the car. In a vertical groove, a', in the inner side of one of the uprights a', below the floor of the platform, is journaled at g the double bell-crank lever G, said lever being provided at its lower 70 end with two arms, g' g'', the free ends of which are respectively above and below the fulcrum of said lever, as shown in Fig. 2, so that when the lever is turned upon its fulcrum the inner ends of the arms g' g'' will be moved, 75 the one nearer to and the other farther from the center of the car. The upper arm, g', is connected by a rod, H, to the bar d of the dogs D, and the free end of the lower arm, g'', is connected by the rod H' to the bar d', which 80 unites the dogs D', so that moving the upper end of the long arm g'' of the bell-crank lever G inward will draw the dogs D D' into the tubes E and out of engagement with the racks c', but not entirely out of the grooves c. 85

To a bracket, a'', secured to the under side of the cross-bar a'', is pivoted a bell-crank lever, I, the lower arm of which, i, is connected by a link, i'', to the upper end of the arm g'' of the lever G, and the other end of which lever 90 I is connected by a loop, i'', to a hook, J, secured to the lower end of the lifting-rope (not shown) in the usual manner, the link i'' surrounding the cross-bar a'', and having an in-

terior width just sufficient to allow it to move freely up and down on said cross-bar.

It is evident that when the lifting-rope is taut and unbroken the inner end of the lever 5 I will be drawn up against the under side of the cross-bar a^2 by the weight of the car; but when the lifting-rope is broken or suddenly slackened the springs F will throw the dogs and the bars d d' outward and cause the upper end of the lever G to swing outward and draw the inner end of the lever I out of contact with the cross bar a^2 into the position shown in Fig. 2.

When the car is supported by the lifting-rope, the dogs do not interfere with the descent of the car, being held out of engagement, as above described; but the moment the rope breaks the dogs engage the racks and prevent the car from falling with a crash.

20 I claim as my invention—

1. The combination of the car provided with a platform, the rack-standards provided with racks, dogs sliding in said platform and connected in pairs, springs arranged between said 25 pairs of dogs and thrusting the same outward, a lever pivoted on said car and provided with two arms, the free ends of which are, respectively, above and below the fulcrum of said lever, rods connecting said arms with said pairs of dogs, respectively, said lever being provided with a third arm adapted to be connected to the lifting-rope of said car to draw and hold said dogs out of engagement with said racks when said rope is unbroken and to 30 allow said dogs to engage said racks when said rope is broken, as and for the purpose specified.

2. The combination of the car provided with a platform, the rack-standards provided with 40 vertical grooves and with racks arranged in the deepest parts of said grooves, dogs sliding

in said platform and connected in pairs and normally projecting into said grooves, springs arranged between said pairs of dogs and thrusting the same outward, a lever pivoted on said car and provided with two arms, the free ends of which are, respectively, above and below the fulcrum of said lever, rods connecting said arms with said pairs of dogs, respectively, said lever being provided with a third arm 45 adapted to be connected to the lifting-rope of said car to guide said car, to draw and hold said dogs out of engagement with said racks when said lifting-rope is unbroken, and to allow said dogs to engage said racks when said 50 rope is broken, as and for the purpose specified.

3. The combination of the car provided with a platform, the rack-standards provided with racks, parallel tubes secured in said platform 60 and provided with lateral slots, dogs sliding in said tubes, bars connecting said dogs in pairs through said slots, springs arranged in said tubes, a spring between each dog and a dog of the other pair and thrusting said dogs 65 outward, a lever pivoted on said car and provided with two arms, the free ends of which are, respectively, above and below the fulcrum of said lever, rods connecting said arms with the respective bars which connect said dogs in 70 pairs, said lever being provided with a third arm adapted to be connected to the lifting-rope of said car, as and for the purpose specified.

In witness whereof I have hereunto set my 75 hand, in presence of two subscribing witnesses, this 20th day of April, A. D. 1887.

VITAL GÉLINEAU.

Witnesses:

ALBERT M. MOORE,
JOHN WYMAN.
